SURFACE ORNAMENTATION OF WALLS.

No. 18,427.

Patented July 3, 1888

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,427, dated July 3, 1888.

Application filed March 17, 1888. Serial No. 267,576. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

The accompanying photograph is a plan or face view of my design.

10 A is a quadrangular elevation showing, first, four beveled or inclined sides, as B; second, a flat face or ledge, C, and, third, a pyramidal elevation, D, having curved, rounded, or convex faces, as E. Parallel to the sides of the 15 elevation A appear rounded or convex elongated elevations F, the extremities G of which are inclined or beveled.

At the corners of the design appear rectangular pyramidal elevations H, having rounded or convex sides I. Between the elevation A 20 and the adjacent elevations F is a channel, M. Between each elevation H and the adjacent ends of the elevations C are channels N O.

I claim—

The design for surface ornamentation of 25 walls, &c., substantially as herein shown and described.

FREDERICK KOSKUL.
